Inventor
J. F. STEWART,

UNITED STATES PATENT OFFICE.

JOHN F. STEWART, OF WILKINSBURG, PENNSYLVANIA.

KEY-HOLDER.

No. 905,015.

Specification of Letters Patent.

Patented Nov. 24, 1908.

Application filed March 18, 1908. Serial No. 421,791.

To all whom it may concern:

Be it known that I, JOHN F. STEWART, a citizen of the United States of America, residing at Wilkinsburg, in the county of Allegheny and State of Pennsylvania, have invented certain new and useful Improvements in Key-Holders, of which the following is a specification, reference being had therein to the accompanying drawing.

10 This invention relates to key holders, particularly designed for preventing the burglarizing of buildings having doors secured and locked by keys.

15 The primary object of my invention is, to prevent a person from surreptitiously shifting a key, or removing the same from a lock.

Another object of my invention is to provide a simple and inexpensive key holder that can be easily and quickly applied to a 20 lock of a door for maintaining the key in a fixed position within a lock.

With these and other objects in view which will more readily appear as the invention is better understood, the same consists in the 25 novel construction, combination and arrangement of parts to be presently described and then specifically pointed out in the appended claims.

30 In the drawings: Figure 1 is a front elevation of a key holder constructed in accordance with my invention, the same being illustrated as applied to a key. Fig. 2 is a front elevation of the key holder as detached from a key, Fig. 3 is a cross sectional view 35 of a key holder as engaging the key, and Fig. 4 is a side elevation of the key holder.

In the accompanying drawings, 1 designates a door having a lock 2 of a conventional form, this lock being used in connection with a door knob 3 and a door knob shank 4, the latter being located directly above the key hole 5 of the lock. For operating the lock 2 a key 6 is used, this key 45 having a skeleton handle or enlargement 7 for facilitating the manipulation of the key.

My key holder is constructed of a single piece of wire, one end of which is bent to form a hook 8 adapted to embrace the door knob shank 4. The opposite end is bent to 50 form an oblong loop 9 and this loop is adapted to extend through the skeleton handle or enlargement 7, and prevent its rotation in the lock 2. In completing the loop 9 the end of the piece of wire is bent to encircle an intermediate portion of the wire, the engagement being such as to prevent any

relative movement of the sides of the loop in a direction to decrease the width of the loop, so that the loop is formed of permanent shape and of predetermined size.

When the key is positioned as shown in Figs. 1 and 3 of the drawings with the handle or enlargement 7 at right angles to the key hole 5, it is impossible to withdraw the key from the lock, and in order to maintain 65 the key in this position, the loop 9 of the key holder is inserted in the handle or enlargement.

When the key is positioned in the key hole with the plane of the axis of the opening of the key extending through the knob shank, the placing of the loop portion of the holder through the key opening places an obstruction in the path of rotative movement of the key of such character as to prevent any 75 movement of the key whatever, except by absolutely breaking the holder, the form of the latter being such as to successfully resist pressure exerted in a direction to decrease the width of the loop; hence the key is held 80 fixedly against movement and any liability of moving the lock-bolt by a manipulation of the key is prevented.

It will be of course understood that this key holder is used upon the inner side of a 85 door, after the same has been locked, the key holder being applicable to ward-locks and various kinds of locks manipulated by keys.

The simplicity of construction entering 90 into my key holder permits of the same being manufactured at a comparatively small expense and effectively used for preventing the burglarizing of a house. It is not only applicable to the front doors of a house, but 95 may be used in connection with the doors of the various compartments thereof.

Having now described my invention what I claim as new, is:—

1. A key-holder for preventing movement 100 of a key in a key-hole, said holder being formed of a single piece of wire having one of its ends formed with a hook adapted to embrace the shank of a door knob, and having its other end bent to form a permanently 105 closed oblong loop adapted to pass through an opening in the key, said loop being of predetermined size and formed to present obstructions against a free movement of the sides of the loop relatively to each other to 110 change the form of the loop.
2. A key-holder formed of a single piece

of wire having one of its ends formed with a hook, and having its opposite end bent around and substantially encircling and closely fitting the wire at an intermediate point in the length of the wire to form an oblong loop of predetermined size, the bent encircling end forming an obstruction against a free movement of the sides of the

loop relatively to each other to change the form of the loop.

In testimony whereof I affix my signature in the presence of two witnesses.

JOHN F. STEWART.
